DESIGN FOR A GOLF CLUB HEAD

John Jay Jakosky, Lawrence, Kans.

Application June 14, 1943, Serial No. 110,445

Term of patent 14 years

(Cl. D34—5)

To all whom it may concern:

Be it known that I, John Jay Jakosky, a citizen of the United States, residing at Lawrence, in the county of Douglas and State of Kansas, have invented a new, original, and ornamental Design for a Golf Club Head, of which the following is a specification, reference being had to the accompanying drawing, forming a part thereof.

Fig. 1 is an elevational view of a golf club head presenting one striking face embodying my new design.

Fig. 2 is an elevational view presenting a second striking face,

Fig. 3 is an elevational view presenting a third striking face,

Fig. 4 is a top plan view; and

Fig. 5 is a bottom plan view thereof.

I claim:

The ornamental design for a golf club head, as shown.

JOHN JAY JAKOSKY.
